MOTORCYCLE WINDSHIELD AND HANDLEBAR UNIT

Frank G. Stone, Long Beach, Calif., assignor of one-half
to Peter Mead, Canoga Park, Calif.

Filed Apr. 8, 1968, Ser. No. 11,352

Term of patent 14 years

Int. Cl. D12—11, 99

U.S. Cl. D90—1

FIGURE 1 is a perspective view of a motorcycle windshield and handlebar unit, showing my new design;

FIGURE 2 is a front elevation view thereof;

FIGURE 3 is a right side elevation view thereof as seen from the left in FIGURE 2; the other side, not shown, is a mirror image of the side shown;

FIGURE 4 is a rear elevation view thereof; and

FIGURE 5 is a top plan view thereof.

I claim:

The ornamental design for a motorcycle windshield and handlebar unit, substantially as shown and described.
